(57) **CLAIM**

The ornamental design for a combination body harness and detachable paint bucket for painter, as shown and described.

DESCRIPTION

FIG. 1 is a perspective view of the combination body harness and detachable paint bucket for painter embodying the design of the present invention;

FIG. 2 is a front elevational view thereof;

FIG. 3 is a rear elevational view thereof;

FIG. 4 is a left side elevational view thereof, the right side elevational view being a mirror image thereof;

FIG. 5 is a top plan view thereof;

FIG. 6 is a bottom plan view thereof; and,

FIG. 7 is a reduced perspective view of the combination body harness and detachable paint bucket for painter embodying the design of the present invention; the broken lines depict environmental structure and form no part of the claimed design.
